Primary Examiner—Prabhakar G. Deshmukh*Attorney, Agent, or Firm*—Anthony J. McNulty[57] CLAIM

The ornamental design for a pool table in the shape of a boat with five pockets, as shown and described.

DESCRIPTION

FIG. 1 is a top plan view of a pool table in the shape of a boat with five pockets showing my new design;

FIG. 2 is a side elevational view thereof, the opposite side being a mirror image thereof;

FIG. 3 is a bottom plan view thereof;

FIG. 4 is a front elevational view thereof; and,

FIG. 5 is a rear elevational view thereof.

The broken line showing of pool legs is for illustrative purposes only and forms no part of the claim.
